(57) CLAIM

The ornamental design for a container for holding face cream, as shown and described.

DESCRIPTION

FIG. 1 is a top plan view of a container for holding face cream showing my new design;

FIG. 2 is a front elevational view thereof;

FIG. 3 is a bottom plan view thereof;

FIG. 4 is a right side elevational view thereof;

FIG. 5 is a rear elevational view thereof;

FIG. 6 is a left side elevational view thereof; and,

FIG. 7 is an isometric view thereof showing my design.
